UNITED STATES PATENT OFFICE.

MARTIN FISCHER, OF ZURICH, SWITZERLAND, ASSIGNOR TO FISCHER MOTOR CORPORATION, A CORPORATION OF NEW YORK.

METHOD OF MAKING ENGINE-CYLINDERS.

1,113,548.

Specification of Letters Patent. Patented Oct. 13, 1914.

Original application filed January 12, 1912, Serial No. 670,904. Divided and this application filed April 29, 1914. Serial No. 835,103.

To all whom it may concern:

Be it known that I, MARTIN FISCHER, a citizen of Switzerland, a resident of Zurich, in the Canton of Zurich, Switzerland, have 5 invented certain new and useful Improvements in the Method of Making Engine-Cylinders, of which the following is a specification, reference being had to the accompanying drawings, made a part hereof.

10 My invention relates to engines, as shown and described in my application for Letters Patent, filed January 12, 1912, Serial No. 670,904, entitled Combustion-engine of which this is a divisional application.

15 This application relates to method or process of manufacturing a structure embodying the invention fully set forth in said original application, as will hereinafter appear.

20 In the drawings Figure 1 is a vertical section of a cylinder showing valves and recesses with piston in position; Fig. 2 is a transverse section of the cylinder; Fig. 3 is a diagram to illustrate the method of manufacture of cylinder and valves embodying the particular features shown in Figs. 1 and 2.

25 In the drawings 1 is a cylinder having at 1^a an integral head; 2—2 are valves engaging piston 3, and set in recesses 4—4. Each of the valves 2 is a slide valve of crescent form in cross section, each adapted to reciprocate in a recess 4, which is correspondingly crescent shaped in section, that is the 35 space between the surface of the piston and the outer side or back of the recess constitutes a crescent shaped space.

30 Through the sides of the cylinder wall are ports connecting with the recesses and 40 alternately closed and opened by the reciprocation of the slide valves according to the desired cycle of the engine.

45 In the form of slide valve and recess shown it will be particularly noted that the circular section of all the working faces secure an easy working and a safe packing of the surfaces.

50 Parts of my method of construction may be applicable with changes in some of the features of construction; but in the particular form shown the construction may be effected as follows: both bores, forming the guide face of the slide valves, are made first

in the solid cylinder; the slide valves, shaped out of a solid turned and lengthwise cut 55 cylinder, are then placed in the bores and screwed tight from the outside; after this the cylinder is bored. This method may be applicable in small cylinders individually made, but is not intended for quantity production. 60

In motors where the cylinders are always cast with a hollow center for the bore, the construction may be carried out as follows: The working surfaces of the slide valves, as 65 at 4^a Fig. 3 are first bored or turned and may be finished on a circular grinder. The slide valves, still rough on the side intended to engage the piston, but finished on the backs or outside, are then put into place and 70 screened fast by lag screws or any suitable method from the outside. Then the inner face of the cylinder is bored through, finishing the inner surface of the cylinder proper as well as the inner surface of the valve or 75 valves. It will be seen that by this method both faces of the slide valves as well as the cylinder can be produced by turning, boring or circular grinding, in a manner greatly facilitating production. 80

In the first of the two methods above described the valve seat is bored with a tool cutting throughout the circumference of the bore as the solid material in the center of what afterward becomes the cylinder bore, 85 insures the even cutting of the boring tool. While boring the cylinder with the valve pieces secured in their seats, the boring cut of the cylinder proper is also continuously in the material and insures a uniform cut. 90 It has been found that when carefully done there is no tearing or chipping of the metal where the material above the valve joins the cylinder surface. This may be particularly distinguished if we consider an attempt to produce this construction of cylinder by first boring the cylinder throughout and then cutting the recesses in the sides with an arbor supported at either end. In this way the tool would cut the recess only 95 during a part of its revolution, being a one sided cut which would tend to spring the arbor and prevent accuracy. Such inaccuracy would be accentuated when boring the cylinder with integral head, as shown in the 100 drawings, resulting in great difficulty if not 105

the impossibility of machining sufficiently close to dimensions to make the valve operation possible without prohibitive expense.

While I have illustrated and described one form of practising my method it is possible to modify it in some respects without departing from my invention, but

What I claim and desire to secure by Letters Patent is:

10 1. A process for the construction of a motor of the character described consisting in boring the slide valve tracks, placing slide valves cut out of a solid cylinder in said bores, thereupon boring the cylinder proper, whereby all working surfaces are produced by turning, boring or circular grinding.

20 2. A method for the construction of motors consisting of boring a recess longitudinally in the side of the cylinder, inserting therein a slide valve, and finish-boring or grinding of the internal surface of the cylinder with the valve in position.

25 3. A method of machining engine cylinders consisting of forming in a hollow cylinder casting a longitudinal depression in the side to constitute a valve seat, forming the outside or back of a sliding valve to conform to said seat and securing it in the

seat, and thereupon finish-boring the cylinder and interior face of the valve at the same time.

4. A method of constructing an engine cylinder and valve seat consisting of effecting a sectional cylindrical cut from the inside into the inner wall of the cylinder, and thereafter finishing the main inner surface of the cylinder.

5. A method of machining the interior of an engine cylinder with valve seat consisting of cutting on a cylindrical section the material away from the side of the proposed interior cylindrical surface on a radius less than the radius of the cylinder boring, fitting and securing a valve in said cylindrical sectional recess, and thereafter finishing the interior wall of the cylinder and the valve at the same time.

In testimony whereof I have signed my name to this specification, in the presence of two subscribing witnesses, this 3rd day of April, 1914.

MARTIN FISCHER.
